UNITED STATES PATENT OFFICE.

ARTHUR D. PRATT, OF SHORT HILLS, NEW JERSEY, ASSIGNOR TO THE BABCOCK & WILCOX COMPANY, OF BAYONNE, NEW JERSEY, A CORPORATION OF NEW JERSEY.

SUPERHEATER AND SETTING THEREFOR.

Application filed July 27, 1921. Serial No. 487,857.

To all whom it may concern:

Be it known that I, ARTHUR D. PRATT, a citizen of the United States, residing at Short Hills, in the county of Essex and State of New Jersey, have invented certain new and useful Improvements in Superheaters and Settings Therefor, of which the following is a specification.

One of the objects of my invention is the provision of a cheap, compact and efficient independently fired superheater in which all the parts of the superheater, including the headers, are enclosed in the setting, and in which the steam flows in series in a generally reverse direction to the flow of gases. Where the connections between the sections of the superheater are arranged without the setting, there is a considerable drop in steam pressure, which is objectionable, both because of the decreased efficiency and of an undesirably low pressure of the superheated steam, and which is particularly objectionable where the superheater handles low pressure steam. In accordance with my invention, in which the superheater is entirely enclosed in the setting, the foregoing difficulties are overcome.

While I have described my invention as applicable to a superheater, it will be understood that certain features thereof are applicable to fluid heaters other than superheaters.

My invention will be best understood by reference to the accompanying drawings, in which Figure 1 is a horizontal sectional view through a superheater and the setting therefor embodying my invention, and taken along the plane of the line 4—4 of Fig. 2; Fig. 2 is a vertical longitudinal section taken through Fig. 1; Fig. 3 is a vertical transverse section taken on the line 6—6 of Fig. 1.

Like reference characters indicate like parts throughout the drawings.

Referring, now, to the drawings, and first to Figs. 1 to 3, I have indicated, generally, at 10 a superheater which is enclosed by the setting, the front and rear walls of which are indicated at 11 and 12, respectively, the side walls at 13, and the roof at 14, which, together with the floor beneath the superheater will, for convenience, be referred to in the claims as enclosing walls. An oil burner 32 is used for supplying fuel to the furnace. The flame from the burner is pro-

jected to the rear of the furnace, from whence it ascends into a chamber 34, from which the gases pass through the checker-work 24 to the superheater 10. An access door 35 is preferably provided for the combustion chamber, and an access door 36 for the chamber 34. Dusting openings 30 are also preferably provided in the wall of the setting opposite the superheater.

The superheater 10, which is located in a space at the rear of the bridge wall 16, comprises headers 17, which are shown as cylindrical in form, and preferably located near the bottom of the enclosure, and which extend transversely across the superheater enclosure. The inlet header 17^a is preferably located adjacent to the rear wall 12, the outlet header 17^b is preferably located adjacent to the bridge wall 16, and the intermediate headers 17^c and 17^d are preferably located immediately above partition walls 18, as best shown in Fig. 2. Groups of U-shaped superheater tubes are connected to successive headers and extend upwardly therefrom longitudinally of the superheater enclosure. In Fig. 2, three such groups are shown, the first group 19^a connecting the header 17^a to the adjacent intermediate header 17^c, the second group 19^b connecting the intermediate headers 17^c and 17^d, and the third group 19^c connecting the outlet header 17^b to the adjacent intermediate header 17^d. The adjacent headers of the U-tubes of the various groups are thus connected to the same headers, causing the steam to flow from the groups 19^a to the header 17^c, from the headers 17^c directly to the tubes of group 19^b, and so on to the outlet header 17^b, whereby steam flows through said tubes and headers in series. The tubes of each group are preferably arranged in a plurality of rows, as best shown in Fig. 1, the tubes of the successive rows preferably being staggered with reference to each other, as best indicated in Fig. 1. In order to direct the gases longitudinally over the superheater tubes, baffles or walls 20 and 21 are formed by the tubes themselves between the groups 19^a, 19^b and 19^c of the superheater tubes, the tubes of outer rows of adjacent groups lying side by side to form a continuous baffle, as indicated in Fig. 1. The tubes at the end of the baffle are bent away from each other, as at 22, to form an opening through which the gases pass from one chamber to the next, the tubes

at the alternate ends of successive baffles being bent away from each other, as indicated in Fig. 2. In the form illustrated, where there are but three groups of tubes, 5 there are only two such baffles and the tubes at opposite ends of the two baffles are thus bent away from each other. The baffle 20 extends downwardly from the roof 14 between the groups 19^b and 19^c, the opening 10 22 being formed between the baffle 20 and the header 17^d. The second baffle 21 extends upwardly from the second header 17^c between the groups 19^a and 19^b, an opening 23, similar to the opening 22, being formed 15 between the top of the baffle and the roof. The intermediate headers 17^c and 17^d are thus located in the planes of the baffles 20 and 21. Preferably checkerwork 24 is provided at the top of the bridge wall 16, and 20 extending to the roof 14, to assist in thoroughly mixing the gases and to protect the upper ends of the superheater tubes above the bridge wall from the direct radiant heat of the furnace. The checkerwork is particularly useful in protecting the front tubes 25 located adjacent to the combustion chamber when the steam passes through the tubes in series from the rear to the front, as here shown, and where the front tubes are, therefore, operated at a high temperature.

Saturated steam is introduced to the inlet header 17^a at 26, a valved outlet pipe for the superheater being indicated at 27.

In operation, the gases from the combustion chamber 34 pass through the checkerwork 24 and downwardly longitudinally of the tubes of the group 19^c, through the opening 22, upwardly over the group of tubes 19^b to the opening 23, and downwardly over the 40 group of tubes 19^a, from which they pass through the outlet flue 31. The steam which enters the inlet header 17^a through the inlet pipe 26, passes through the group of tubes 19^a to the first intermediate header 17^c, thence through the group of tubes 19^b to the second intermediate header 17^c, and thence through the third group of tubes 19^c to the outlet header 17^b. The steam thus 45 passes through the tubes and headers in series in a generally reverse direction to the flow of the gases, thereby increasing the efficiency of the superheater. It will also be apparent that by flowing through the tubes and headers of the superheater in series in 50 the manner described, in case the steam is uniformly distributed in the inlet header 17^a, the uniform distribution of steam throughout the tubes of the superheater will be preserved, and in case of any uneven distribution of steam in the inlet header, the 55 series flow of the steam through the various tubes and headers will tend evenly to distribute the steam to the various tubes as the steam passes in series through the tubes of 60 the headers.

In the form of my invention illustrated in Figs. 4, 5 and 6, an oil burner 32 is used for supplying fuel to the furnace. In this case, a roof between upright sections 11^a and 11^b of the front wall is provided, so that the flame from the burner is projected to the rear of the furnace, from whence it ascends 70 into a chamber 34, from which the gases pass through the checkerwork 24 to the superheater 10^a. An access door 35 is preferably provided for the combustion chamber, and an access door 36 for the chamber 34. In this form of my invention, I have shown the baffles 20^a and 21^a between the groups 19^a, 19^b and 19^c of the superheater tubes formed by the tubes themselves, the tubes of outer rows of adjacent groups lying side by side to form a continuous baffle, as indicated in Fig. 4. The tubes at the end 75 of the baffle are bent away from each other, as at 36, to form an opening through which the gases pass from one chamber to the next, the tubes at the alternate ends of successive baffles being bent away from each other, as indicated in Fig. 5. In the form illustrated, where there are but three groups of tubes, there are only two such baffles, and the tubes 80 at opposite ends of the two baffles are thus bent away from each other.

What I claim and desire to secure by Letters Patent of the United States is:

1. In a fluid heater and its setting, transverse headers located adjacent to an enclosing wall of the heater, groups of U-shaped tubes connected at their ends to adjacent headers, the adjacent ends of adjacent groups being connected to a common header, some of the tubes of each group being arranged side by side to form a baffle but bent away from each other at alternate ends in successive groups, whereby the gases are directed in series over said groups of tubes.

2. In an independently fired superheater and its setting, transverse headers located adjacent to an enclosing wall of the superheater, groups of U-shaped superheater tubes connected at their ends to adjacent headers, the adjacent ends of adjacent groups being connected to a common header, some of the tubes of each group being arranged side by side to form a baffle but bent away from each other at alternate ends in successive groups, whereby the gases are directed in series over said groups of tubes.

3. In an independently fired superheater and its setting, transverse headers located adjacent to an enclosing wall of the superheater, groups of U-shaped superheater tubes connected at their ends to adjacent headers, the adjacent ends of adjacent groups being connected to a common header, some of the tubes of each group being arranged side by side to form a baffle but bent away from each other at alternate ends in successive groups to form openings, where-

by the gases are directed in series over said groups of tubes.

4. In an independently fired superheater and its setting, transverse headers located 5 adjacent to an enclosing wall of the superheater, groups of U-shaped superheater tubes connected at their ends to adjacent headers, the adjacent ends of adjacent groups being connected to a common header, 10 some of the tubes of each group being ar-

ranged side by side to form a baffle but bent away from each other at alternate ends in successive groups, whereby the gases are directed in series over said groups of tubes, the groups of U-shaped superheater tubes being 15 arranged in a plurality of rows with the tubes of successive rows staggered with reference to each other.

ARTHUR D. PRATT.
